FUEL BURNER

James O. Colclasure, Tulsa, Okla., assignor to
 Pioneer Corporation, Tulsa, Okla., a corpora-
 tion of Delaware

Application August 15, 1932, Serial No. 628,941

2 Claims. (Cl. 299—140)

The invention relates to fuel burners, and has for its object to provide means whereby a propelling fluid is deflected in relation to an oil duct outlet end in a manner whereby a vacuum is formed adjacent said end, thereby facilitating the spraying and projecting operation.

A further object is to provide means adjacent the discharge end of an oil duct of a burner whereby a propelling fluid is deflected angularly away from the oil duct end and angularly outwardly and towards the oil duct end, thereby forming a vacuum pocket adjacent the oil duct end for sucking oil through the duct and facilitating the mixing and spraying operation.

15 A further object is to provide an oil burner having adjacent oil and propelling fluid chambers connected by an oil duct, and a shoulder adjacent the discharge end of the oil duct and inclining at an acute angle to the axis of the oil duct in a position whereby propelling fluid will be projected away from the duct end.

A further object is to provide the propelling fluid passage with an angular deflecting shoulder positioned whereby the propelling fluid will be deflected towards and away from the duct discharge end against an opposing angular wall positioned whereby, not only a vacuum pocket is formed around the duct discharge end, but means whereby the mixed fluid or gases will be discharged upwardly towards the bottom of a boiler, still, furnace and the like.

A further object is to provide the burner head at the discharge end of the fluid propelling passage with a forwardly extending drip lip having a forwardly flared channel in the upper side thereof, thereby allowing the gasified air to be discharged fanwise without dripping or slobbering.

A further object is to provide in combination with an oil burner nozzle having a downwardly extending oil duct, means whereby a propelling fluid, immediately before it reaches the discharge end of the oil duct, will be constricted by a forwardly and downwardly inclined arcuate shoulder and deflected against a flat upwardly and outwardly inclined wall opposite the discharge end of the oil duct, thereby forming a vacuum pocket around the discharge end of the oil duct for facilitating the gasification of the oil.

50 With the above and other objects in view the invention resides in the combination and arrangement of parts as hereinafter set forth, shown in the drawing, described and claimed, it being understood that changes in the precise embodiment 55 of the invention may be made within the scope

of what is claimed without departing from the spirit of the invention.

In the drawing:

Figure 1 is a perspective view in longitudinal section through the burner.

Figure 2 is a front elevation of the burner.

Figure 3 is a vertical longitudinal sectional view through the burner.

Figure 4 is a top plan view of the burner.

Figure 5 is a vertical longitudinal sectional view through a modified form of burner, showing a downwardly and forwardly inclined oil duct.

Referring to the drawing, the numeral 1 designates the body of the burner and 2 an oil chamber therein, and into which oil is discharged through an oil supply pipe 3. Extending downwardly through the body 1 and connecting the chamber 2 and the chamber 4, through which a propelling fluid passes from the supply pipe 5, is an oil duct 6. In devices of this character heretofore constructed, the air or other propelling fluid passes through the chamber 4 and entrains oil or other fluid from the lower end 6a of the duct 6.

To overcome the above difficulty the air supply pipe 10 discharges its contents against a downwardly and forwardly inclined shoulder 7, arcuate in vertical transverse cross section and located rearwardly of the discharge end 6a of the oil duct. The air is deflected downwardly against the forwardly and upwardly inclining wall 4a of the chamber 4 and thence upwardly by said wall, forming a vacuum pocket 8.

It will be noted that the vacuum pocket 8 is at the lower end of the oil duct 6, consequently oil will be sucked from said lower end of the duct into the air train, so that it will be thoroughly broken up and gasified as it is discharged forwardly and upwardly into a furnace, boiler, still or the like.

By discharging forwardly and upwardly a decided advantage is obtained as a flame will be discharged upwardly towards the bottom of a boiler, still, furnace or the like, when the device is used beneath the same. The upwardly and forwardly inclined deflecting surface 4a terminates in a downwardly and forwardly inclined fan shaped discharge channel 9, therefore it will be seen that the gasified fuel will spread over a relatively large surface horizontally, being limited only by the side flanges 10, clearly shown in Figures 4 and 2. By inclining the surface 9 downwardly the possibilities of dripping or slobbering are reduced to a minimum, and it will be noted by referring to Figures 3 and 5, the flat surface 9 is carried by a forwardly extending lip 11, extending beyond 110

the forward end of the body 1, on which particles of fuel may collect, therefore any particles of fuel which may collect on the forward end of the body member 1 will be entrained and projected forwardly and upwardly with the gasified liquid. The course of the fuel through the device is indicated by the arrows *a*, and the course of the propelling fluid, for instance air, is shown by the arrows *b*, and by referring to 10 said arrows in the chamber 4 adjacent the lower end 6a of the duct 6, it will be seen that the vacuum pocket 8 is formed at the lower end of the oil duct.

The body 1 is provided with a clean out plug 15 in alignment with the fuel port 6, and which plug when removed allows access of a tool or instrument into the fuel port, said plug being designated by the numeral 12.

Referring to the modified form shown in Figure 5, the fuel port 13 inclines downwardly and forwardly towards the vacuum pocket 4, thereby facilitating the feeding of fuel to the vacuum chamber in a forward and downward direction for entrainment with the propelling fluid.

From the above it will be seen that a fluid burner is provided with means whereby a vacuum pocket is formed by the propelling fluid, for instance air at high velocity at the discharge end of the fuel port, thereby increasing the mixture 30 before it is projected from the end of the burner. It will also be seen that the fuel is directed upwardly in a fanwise shape, thereby providing a burner particularly adapted for use beneath a boiler, still, furnace or the like, and for distributing 35 the flame over a large area.

The invention having been set forth what is claimed as new and useful is:—

1. A fluid burner comprising a body member having a fuel receiving chamber in the upper side 40 thereof, a pressure fluid chamber in the lower side thereof terminating in a discharge orifice,

said pressure fluid chamber having its upper walls horizontal and its lower wall inclining upwardly and outwardly, a port of communication between said chambers, the discharge end of said port of communication being spaced from the ends of the upper wall of the lower chamber, a rear extension of said pressure chamber having an upward and rearwardly inclined upper wall, said upwardly and rearwardly inclined upper wall forming means whereby propelling fluid is projected downwardly into engagement with the upwardly and outwardly inclined bottom wall of the lower chamber at a point opposite the port of communication between the chambers, said upwardly and outwardly inclined wall deflecting the propelling fluid upwardly and outwardly from said point opposite the port of communication between the chambers whereby entrained fluid fuel will be projected upwardly and outwardly from a point adjacent the discharge end of the port of the communication between the chambers. 80 85 90 95

2. A fluid burner comprising a body member having an upper fuel chamber, a lower propelling fluid chamber having a discharge orifice, said lower propelling fuel chamber having its lower side inclined upwardly and outwardly, a port of communication between the chambers and discharging into the lower chamber at its upper side and spaced from the ends thereof, a rearward extension of said fluid propelling chamber 100 having an upwardly and rearwardly inclined deflecting wall spaced rearwardly from the port of communication, said upwardly and rearwardly inclined deflecting wall being positioned whereby propelling fluid passing through the lower chamber extension will be deflected into engagement with the upwardly and outwardly inclined bottom of the lower chamber at a point opposite the port of communication between the chambers. 105 110 115
